EXPANDING CLOSING CAPSULE FOR BOTTLES AND OTHER CONTAINERS

Willy Faltthauser, Munich, Germany

Application May 24, 1932, Serial No. 613,241
In Germany September 25, 1930

6 Claims. (Cl. 215—95)

Closing devices or capsules for bottles and other containers in which the capsule is expanded in applying or removing the same and closed to seal the container are already known.

5 These closing devices are, in most cases, made to consist of the capsule proper provided with claws, a packing disk between the capsule and the upper edge of the head of the container and a clamping ring adapted to be placed over the 10 claws of the capsule to prevent accidental opening thereof.

It has, however, been ascertained that these closing devices are not always tight, particularly in cases where the closure is subjected to 15 pressure from within the container. The cause thereof may be traced to the construction of the capsule, as well as of the packing disk and of the clamping ring.

It is an object of the present invention to overcome these drawbacks and to provide a closure 20 for bottles and other containers, adapted to remain tight even when subjected to considerable pressure from within.

Another object is to provide a novel form of 25 closure for bottles or other containers which may be readily applied and removed without the use of special tools.

A further object is to provide a capsule having 30 a packing therein and so formed that the packing is held in close proximity to the neck of the container when pressure is applied to the capsule from within the container.

Another object of the invention is to provide a 35 closure for bottles or other containers that are formed with a cylindrical neck having a shoulder adjacent the top thereof which closure is formed with an annular depression in alignment with the neck of the container.

Other objects of the invention are to provide 40 a novel form of severable retaining ring for preventing accidental removal of the closure from the receptacle, to provide means carried by the capsule for engaging the retaining ring to deform the same and prevent removal thereof without destroying or defacing the ring and to provide a capsule having claws and means to prevent flexing thereof.

Another object of the invention is to provide 45 a receptacle formed to receive and hold a closure thereon and provided with means to prevent displacement of the retaining ring after it has been applied to the closure.

These and other objects and features of the 50 invention will appear from the following description thereof in which reference is made to

the typical forms of the invention illustrated in the drawings by way of example. In the drawings

Fig. 1 represents a side elevation of a bottle 5 head provided with a capsule in accordance with a preferred form of the invention, whilst

Fig. 2 represents a section on an enlarged scale through a portion of the form of the invention shown in Fig. 1.

Figs. 3 and 4 are side views of preferred forms 10 of the capsule.

Fig. 5 is a sectional view of a portion of the form of capsule shown in Fig. 4 taken on the line V—V.

Figs. 6 and 7 are plan views of preferred forms 15 of the capsule.

Figs. 8, 9, 10 and 11 are side views partly in section of various forms of clamping ring which may be employed.

Fig. 12 is a plan view of the form of clamping 20 ring illustrated in Fig. 10.

Fig. 13 is an enlarged view of a portion of a band of material used in producing the form of clamping ring illustrated in Fig. 8.

Figs. 14 and 15 illustrate forms of the present 25 invention applied to metallic receptacles.

In the drawings the numeral 1 represents a bottle head provided with a shoulder adjacent the top thereof. The capsule shown in Figs. 1 and 2 comprises a cover part 2 extending across 30 the top of the bottle. The outer edges thereof are turned downwardly substantially vertically and formed with slots 3 extending nearly to the top of the downwardly-turned portion. The lower extremities of the downwardly-extending 35 portions are turned sharply inward forming a plurality of claws 4 adapted to engage beneath the shoulder on the bottle or container to hold the closure in place. The center of the cover part is bowed upwardly above the periphery 40 thereof when the capsule is in its "closed" position with the claws engaging the lower portion of the shoulder on the container but can be flexed downwardly so that the center of the cover part is below the periphery in order to 45 cause the claws 4 to spring outwardly away from the shoulder on the bottle to enable the capsule to be removed. As is usual with closures of this type the cover part when forced beyond the plane in which the periphery lies snaps upward 50 or downward, causing the claws 4 to be forcibly opened or forcibly to engage the shoulder of the bottle or container. The capsule is preferably formed of relatively flexible metal or other material capable of being readily flexed and the 55

claws 4 are formed integral with the cap and of the same relatively flexible material as the cover part of the cap, but are rendered substantially rigid by forming embossed or struck up portions thereon as shown by the projections 6, 6' in Fig. 3 and the ridges 7 of Fig. 4. Fig. 5 shows an embossed ridge 7 in section to illustrate the manner in which the claws are strengthened. The cover part 2 is normally of greater diameter than the top of the bottle so that a space is provided between the upper part of the claws 4 and the top of the bottle as shown in Fig. 2 for purposes explained more fully hereafter.

In order to prevent accidental opening of the claws during shipping and storage of the containers and to prevent "blow offs" due to excessively high pressure within the bottle a clamping or safety ring 3 surrounding the claws 4 is provided. In accordance with the present invention the cover part 2 is provided with an accentuated annular groove or depression 5 extending downward and situated adjacent the outer edge of the cover part adjacent the periphery thereof and in alignment with the neck of the container as shown in Fig. 2. The grooved portion of the cover part bears against the upper surface of a suitable packing or washer 22 positioned within the capsule and serves to force the washer tightly against the top of the bottle or container to seal the same effectively. Since the force with which the cover part of the capsule bears against the washer 22 is applied to only a very limited annular area of the washer, a relatively high pressure per unit of area is obtained, and therefore it will be apparent that an effective seal is produced with the application of a relatively small force such as that applied by the upward spring thrust of the center of the capsule which holds the claws 4 beneath the shoulder and forces the groove 5 against the packing and the top of the neck of the container.

It will be apparent that upon flexing the upwardly bowed center portion of the capsule to apply or remove the same the diameter thereof is increased as the center is forced through the plane of the periphery of the capsule. The annular depression 5 of the capsule facilitates this expansion of the center portion due to the slight outward bending of the inner wall of the depressed portion and the resultant narrowing of the annular groove. Because of this construction of the annular depression which renders flexing of the center portion of the capsule relatively easy, it is possible to make the capsule of heavier material than would otherwise be possible, and as a result the strength of the claws 4 is considerably greater than in previous spring caps of this general type, so that "blow offs" due to straightening out of the claws are decreased. This feature of the invention also renders it possible to construct closures of this type for bottles and other containers having necks of relatively small diameter since the central portion thereof may be bowed upwardly or dished to a greater extent than would be possible were it not for the outward yielding of the inner wall of the annular depression as the center portion is forced through the plane of the periphery. Furthermore, the heavier construction of the capsule and the increased curvature of the center portion permissible by reason of the annular depression results in greater spring action or tension upon the claws 4 in engaging beneath the shoulder on the neck of the container.

The cover part of this capsule may also be

provided with indentations 8 placed opposite the slots 9 between the claws 4 and adjacent the groove 5. Owing to the disposition of these indentations the depressing of the center of the cover part and with it the expansion or closing of the claws 4 will be facilitated. Instead of the indentations the cover part may be scratched beside the groove or crease 5 as indicated at 10 in Fig. 7.

The clamping ring 3 already referred to preferably consists of metal and may be made from a band or tube. In accordance with the present invention this ring is preferably reinforced at its edges, so that it may be made from very thin material, yet possess sufficient stiffness to be applied by means of machines. The reinforcements may be formed by flanging and folding over the edges of the ring, as has been indicated at 11 in Figs. 8 to 11. The ring 3 may be formed with a strip or band of metal 13, one end of which 20 serves as a tearing flap 14 and is narrower than the remainder of the band. The portion of the band adjacent the tearing flap constitutes an overlap when the band is formed into a ring and is provided with teeth 12 on the edges of the band 25 between the tearing flap 14 and the band proper as shown in Figs. 8 and 13. The edges of the band are then folded over the teeth 12 securing the band in the form of a ring. The teeth 12 dig into the folded edges of the band and in some 30 instances may themselves be folded over with the edge of the band forming a secure bond preventing severing of the band or displacement of the end thereof when the band is placed under tension. 15 represents perforations close to the teeth 12, rendering it possible to tear open the ring by means of the tearing flap 14 so that the claws 4 may be opened and the cap released by depressing the cover part 2 thereof. When producing the ring, the band 13 may be wound twice, 40 so that a double ring is formed, the outer annular part of which 16 (Fig. 9) is engaged by the flanges 11 of the inner annular part 17.

Fig. 10 illustrates a ring produced from a piece of tubing reinforced by a special outer ring 18. 45 The latter is held by the reinforcements 11.

In rings made from tubing, the gripping part of a tearing flap 19 (Fig. 11) is suitably punched out of the wall of the tubing, whilst a somewhat weakened tearing race adjoining said tearing flap, terminates a short distance from the interrupted parts 21 of the edge reinforcements 11, with the result, that the ring possesses the necessary strength.

The rings described possess considerable strength in spite of the thin material from which they are made, so that they may be slipped over the claws 4 by means of machines. Owing to the resistance to the application of the retaining ring offered by the members or projections 6, 6' or 7 the ring engages the claws 4 of the capsule firmly, thus insuring firm application of the capsule to the head of the container 1 and deep penetration of the groove or crease 5 into the thin packing disk or washer 22 (Fig. 2). When slipping the ring over the claws 4 the projections 6 or 7 thereon cause a partial distortion of the ring as shown at 3' in Fig. 1 and in some instances small grooves may be formed in the inner wall of the ring by the stiffening projections, causing the ring to be securely held in position against accidental displacement.

Furthermore the ring is ordinarily destroyed when removed and even if removed surreptitiously without the use of the tearing flap the ring will 75

be so deformed or disfigured by the strengthening projections that it cannot again be employed and therefore the retaining ring also serves as a safeguard for the manufacturer, preventing adulteration or substitution of the contents of the container.

In using the capsule described above the cover part 2 is depressed so that the claws 4 spring open or expand and the capsule is applied to the bottle or container to be sealed. The periphery of the capsule is then pressed downwardly, causing the center of the cover part 2 to snap up and the claws 4 thereby close firmly beneath the shoulder on the bottle, holding the capsule in place and forcing the packing tightly against the top of the neck of the container. In this way, the capsule may be readily removed and replaced as often as desired without the use of any tools or opening instruments. When being shipped or stored the ring is forced over the claws after they have been closed, and the ring is readily removed thereafter by means of the tearing flap 14.

With the construction described above, as soon as an inner excess pressure is produced, as may occur when contents of the container are heated or undergo fermentation after sealing, the center of the cover part 2 tends to bend upwardly or bulge as shown in Fig. 2. However, since the metal or material of which the capsule is made is not elastic, that is, it does not stretch appreciably, the bulging of the cover part is accompanied by a reduction in the diameter of the capsule. The periphery of the cover part and the groove 5 thereon are therefore drawn inwardly, and since the claws 4 are substantially rigid, they are moved inwardly about the outer corner of the shoulder on the container as a pivot so that the periphery of the capsule and the groove or depression 5 assume a position somewhat like that indicated by the dotted lines in Fig. 2. In this way the packing disk or washer 22 is pressed against the top of the bottle or container with greater force as the pressure within the container increases, thus preventing escape of the gases or contents of the bottle.

As shown in Fig. 2, the upper portion of the neck of the container above the shoulder which the tongues of the cap engage is of reduced cross section and tapers toward the top permitting free inward movement of the tongues about the outer edge of the shoulder on the neck when the periphery of the cap is drawn inward by the bulging of the central portion of the cap due to internal pressure. The location of the annular groove or depression on the cap with respect to the shoulder on the neck of the receptacle is such that inward movement of the claws about the outer edge of the shoulder as a pivot causes the groove to move inwardly and downwardly in an arcuate path intersecting the top of the neck of the receptacle, thereby drawing the groove and packing tighter against the top and insuring proper sealing of the receptacle under conditions of considerable internal pressure.

Furthermore, the construction shown avoids the possibility of engagement of the claws with any portion of the neck above the shoulder about which it moves as a pivot, so that inward movement of the upper ends of the claws does not result in outward movement of the lower engaging portions thereof, which would tend to release the cap as pressure increases.

It will also be apparent that the construction illustrated permits limited inward movement of the claws due to the application of the clamping

ring so that the outstanding projections 7 on the claws continually are urged into engagement with the ring. This construction prevents loosening of the ring due to expansion and contraction of the ring or cap with changes in temperature or due to limited stretching of the ring as a result of jarring or long application thereof.

It will be apparent, of course, that the operation of the capsule in producing a tight seal for the container when under pressure is largely independent of the operation of the clamping ring, and therefore these features of the present invention may be employed effectively in constructions in which no clamping ring is employed. It will be understood, however, that the clamping ring enables the closure to be used to seal containers in which considerably higher pressures are encountered.

Figs. 14 and 15 represent two different containers made from sheet metal closed by a cap-sule in accordance with the present invention. From the drawings it will be seen how an unintentional removal of the clamping ring in a downward direction is prevented by a shoulder 23 provided on the container. In a similar way the projection or second shoulder 23 formed on the bottle as shown in Fig. 1 serves to limit the downward movement of the clamping ring 3 when forced over the claws 4 of the capsule illustrated therein.

While the invention has been illustrated and described as applied to preferred forms of capsules or closures it will be evident that the invention is not limited to the particular embodiments thereof herein set forth since the principle of construction and operation thereof are also applicable to other forms and types of closure and closure elements.

I claim:

1. A closure for bottles and other containers having in combination a capsule provided with claws adapted to secure the capsule to the container, a packing disk within the capsule, a clamping ring made from a metal band and adapted to be slipped over the claws of the expanding capsule, said clamping ring being thin-walled and formed with teeth on the portion of the band from which the clamping ring is formed, the clamping ring being folded along the edges thereof to engage and hold the teeth of the band.

2. A closure for bottles and other containers having in combination a capsule provided with claws adapted to secure the capsule to the container, a packing disk within the capsule, a clamping ring made of metal adapted to be slipped over the claws of the capsule, consisting of a band of material the ends of which overlap and are secured together by means of a folded part, and a tearing flap on one end of the band for tearing open the clamping ring for the purpose of removing the capsule.

3. A closure for a bottle or other container comprising an upper circular member, holding claws secured thereto and adapted to engage with a projection on the container, reinforcing means formed on said claws to prevent flexing thereof, said reinforcing means comprising integral outward embossings formed on said claws, and a ring movable into position to engage said embossings to prevent expanding of said claws.

4. A member for securing a closure upon a bottle or other container comprising a band of metal formed into a ring with an overlapping portion and provided with a folded portion on the

- edge of the band adjacent the overlapping portion of the band to secure the same in the form of a ring.
5. A member for securing a closure upon a bottle or other container comprising a band of metal formed into a ring with an overlapping portion and provided with a folded portion on the edge of the band adjacent the overlapping portion of the band to secure the same in the form of a ring and means carried by said band for severing the ring.
6. A member for securing a closure on a bottle or other container comprising a band of metal formed into a ring with an overlapping portion, a fold on the edge of the band engaging the overlapping portion thereof to secure the band in the form of a ring, a tearing flap formed on the overlapping portion of the band, said band being provided with perforations in the overlapping portion facilitating tearing of the band to permit removal of the closure. 5

WILLY FALTSHAUSER. 10
